UNITED STATES PATENT OFFICE.

JOHN W. F. MACDONALD, OF BRIGHTON, MASSACHUSETTS, ASSIGNOR TO THE MERRILL PROCESS COMPANY, A CORPORATION OF MASSACHUSETTS.

HEATING APPARATUS.

1,278,067.

Specification of Letters Patent.

Patented Sept. 3, 1918.

Application filed December 1, 1917. Serial No. 204,946.

To all whom it may concern:

Be it known that I, JOHN W. F. MACDONALD, a citizen of the United States, residing at Brighton, county of Suffolk, and 5 State of Massachusetts, have invented an Improved Heating Apparatus, of which the following is a specification, reference being had to the accompanying drawings, forming part thereof.

10 This invention has reference to an improved apparatus for effecting the circulation of a viscous heat receiving medium from the point or machine at which heat is supplied to and absorbed by said medium and the point or machine at which such absorbed heat is or may be radiated or utilized.

One of the objects of the invention is to provide for the exigencies which may occur in a heating apparatus having a system of 20 piping of considerable length through which heat carrying medium of a viscosity varying with its temperature is mechanically circulated between a point of heat absorption and a point of heat radiation or heat utilization.

Another object of the invention is to provide a novel pumping unit for heating apparatus of the nature herein described.

Other objects of the invention will appear 30 from the following description.

The invention consists in the novel pipe or conduit system having connections by means of which the circuit through which the heat carrying medium travels may be 35 changed with relation to the points of heat absorption or heat utilization either or both.

The invention also consists in the improved heating apparatus having the novel pump unit furnished with the by-pass conduits adapted from their shape and construction to be economically manufactured and installed and to accommodate themselves to unequal expansion or contraction of connected parts.

45 The invention also consists in the means to connect the arms of the conduit circuit at the working or heat radiating side of the circuit relative to the pump.

The invention also consists in such other 50 novel features of construction and combina-

tion of parts as shall hereinafter be more fully described and pointed out in the claims.

Figure 1, represents a side elevation of the improved apparatus parts of the same 55 being broken away.

Fig. 2, represents a plan view of parts of the same.

Fig. 3, represents a sectional view of parts of the apparatus as taken on line 3—3 60 Fig. 1.

Similar characters of reference designate corresponding parts throughout.

In carrying this invention into actual practice one of the primary objects to be 65 attained is the delivery of heat, usually at a temperature above 212° F. but at a temperature that may be predetermined and dependable, within slight variations, at a point distant from the source of said heat. 70

In the transportation and utilization of heat by the circulation of liquid through conduits to provide predetermined dependable temperatures at points distant from the source of heat, it is found that the heat transporting 75 medium must be of a heat retaining nature distinguished by its density from water, steam or gases. In the apparatus herein described, after considerable experimentation, it has been found desirable, if 80

not essential, to make use of a viscous liquid having a consistency at 50° F. somewhat greater than thick molasses. Under temperatures as high as 100° F. this liquid has a tendency to adhere to the wall of the 85 conduit and to so clog said conduit that it would be extremely difficult to effect circulation of the liquid through a conduit of any considerable length wholly filled with the liquid. The operation upon and the 90

control of the liquid in its circulation to various parts of the apparatus is therefore of considerable importance and will be more fully understood by reference to the operation of the new apparatus.

95 In the embodiment of the invention shown in the drawings 5 indicates a heater of any kind having the pipe or conduit 6 exposed to heat in said heater 5 and adapted to receive liquid from an exterior conduit 100

through the conduit 6' and the chamber of valve 7 and to deliver liquid, after its subjection to heat, through conduit 62, to the exterior conduit 8 through the pipe member 9 and the chamber of valve 10. Member 9 preferably has the thermometer 11 adapted to register the temperature of liquid contained in or passing through said member 9 and this member 9 also has the small pipe 12 having the air inlet valve 13 and the automatically acting relief valve 14 both of any well known construction. Conduit 8 communicates through the T pipe connection 15 with the conduit section 16 having the valve 17 and with the conduit sections 18 and 19, the latter of which may be any pipe or conduit located at the point at which radiation of heat is intended to occur or said conduit may constitute a part of or be related to any machine or device by means of which heat supplied from liquid within said conduit 19 is adapted to be utilized for any purpose.

Radiator conduit section 19 communicates through the chamber of valve 20 with the T pipe connection 21 which has the upstanding expansion pipe 22 having the T pipe connection 23 communicating with the chamber 24, of the pressure relief valve 25, which chamber 24 is connected with the pipe fitting 15 whereby undue pressure in that arm of the conduit circuit having such fitting 15 may be automatically relieved by the opening of valve 25 to open a passage 35 to fitting 23 and expansion pipe 22. This pipe 22 is connected by the pipe 26 with the expansion tank 27 located at a suitable distance above the pipe fitting 23 depending upon the degree of static pressure which it is desired to maintain in pipe 22, to act on liquid in or passing through the pipe fitting 21.

Pipe fitting 21 connects through the chamber of the valve 28 with the conduit member 29 of the pump unit which latter includes said member 29, the pump chamber 30, preferably connected with said member 29 by the strainer chamber 31, the conduit header 32 connected with the chamber 50 of valve 7 and having the curved by-pass pipes 33 and 34 which, respectively, are connected by valves 35 and 36 with the pipe 37 upstanding from said conduit member 29.

Conduit member 29 connects with the liquid supply pipe 38, which may be of any suitable size and is connected with a tank or other source of supply of material adapted to be used in this apparatus. This supply pipe 38 has the shut-off valve 39 and may have the pump 40 which latter is however not necessary under ordinary conditions as will hereafter be explained.

The circulating system is constituted by 65 the several conduits and their connections

but said circulating system may, for some purposes, be considered as comprised of the heating unit, the supply and return arms of the circulating system, the heat radiating or utilization unit, the pumping unit and 70 the static pressure and expansion unit and their relation. This circulating system is filled with the viscous liquid above described which preferably has a boiling point above 212° F. and which at ordinary atmospheric 75 temperatures can be circulated with difficulty through the system owing to the excessive pipe friction. Such filling may be accomplished by supplying the liquid through the expansion tank 27 and the pipe 22, or by 80 drawing or forcing the liquid into the system through pipe 38.

With the system of conduits filled with the liquid the operation of circulating the liquid through the system, at atmospheric 85 temperature, by means of the pump 30 would be extremely difficult and an attempt to accomplish this result would probably result in overloading the pump and might cause damage to the system. To overcome 90 such resistance valve 35 is opened, and pump 30 is started whereupon the liquid is forced to circulate through the pump chamber, and thence through pipe 33, valve 35, pipe 37 and conduit member 29 back to the pump 95 chamber 30. This cycle of circulation is so short that the discharge side of the pump is not overloaded but a circulation of the liquid is effected which gradually overcomes its frictional resistance. At a suitable stage 100 in the operation heat may be supplied to the heater 5 and some of such heat eventually is absorbed by the liquid in the conduit 6 whereby the viscosity of such liquid is gradually reduced. When the liquid in conduit 6 has become sufficiently heated valve 105 35 is closed and the operation of pump 30 will cause the circulation of the heated liquid through conduits 8, 16 and 18 to the radiator or machine 19 where heat from 110 said liquid will be radiated or utilized for some purpose. From said radiator or machine 19 the spent liquid will return through the pipe fitting 21 and other connections to the pump 30 and in the course of its 115 movement or circulation from the point or machine of utilization (19) to such pump this column of liquid is subjected to the static pressure of the column of liquid in pipe 22 which supplies deficiencies in said 120 returning column of liquid and also permits the escape, through pipe 22 of gas, air or some of the impurities of the liquid.

The junction of the expansion pipe 22 marks the point in the system to which the 125 circulating liquid is forced and at which point suction of the pump begins. This connection of pipe 22 is placed as close to the pump 30 as is practical so as to reduce the frictional resistance on the suction supply. 130

If the connection for pipe 22 was placed between the radiator (19) and the heater 5 or at a considerable distance from the pump 30 there would be a tendency to starve the pump as the circulating (viscous) liquid column would not ordinarily keep up a sufficient supply to equal that displaced by the pump, therefore the efficiency of the circulation would be reduced.

10 By-pass 34 having the relief valve 36, controlling the passage of liquid to pipe 37 and conduit member 29, is provided in order to protect the pump 30. If for any reason the path of the liquid through the conduit 6 of the heater 5 should become obstructed, for example, should either of valves 7 or 10 be left unintentionally closed and the pump 30 be operated there would be no outlet for discharge of liquid under pressure 15 in the conduit section 32 and as a result of the constantly increasing pressure some part of the apparatus ultimately might be damaged. Relief valve 36 is adjusted to operate under a pressure well within a limit of 20 safety so that when the pressure in by-pass 34 reaches the point at which said valve is set this valve 36 will open and permit a flow back to the suction side of the pump 30.

The by-passes 33 and 34 are constituted 30 by curved pipes arranged and connected so that they may expand and contract without undue strain to themselves or to their connections in either a vertical or horizontal direction.

35 Should valves 17 and 20 or either of them be left unintentionally closed or should the pressure in the conduit of the radiator or machine 19 become excessive relief valve 25 will automatically open a passage from conduit section 8 to the expansion pipe 22 through its connection 23.

As above stated the viscous liquid may be supplied to the circulating system either from the expansion tank 27 or through the 45 pipe 38. In the latter case valve 28 is partially or wholly closed and valve 39 is opened whereupon the suction of pump 30, in its operation, will effect the drawing into conduit member 29 of liquid from said pipe

50 38. If it is desired to draw a supplemental supply of the liquid into the system from said pipe 38 when the system of conduits is partially filled with such liquid valve 28 should preferably be only partly closed.

55 The location of the connection of pipe 38 with the main conduit between the pipe 22 and the pump 30 is of importance as, with such connection and with valve 28 partly open, the action of the pump 30 will result 60 in drawing into the conduit liquid from said pipe 38 as the connection of this pipe 38 is nearer said pump 30 than is pipe 22 and consequently liquid in said pipe 38 will be more subject to the suction of said pump 30. It is also desirable to so locate such connection

of pipe 38 that liquid from this pipe 38 must pass through the strainer chamber 31 before reaching the pump 30.

Having thus described my invention I claim as new and desire to secure by Letters Patent—

1. A heating apparatus for utilizing heat of a traveling body of viscous liquid comprising a heater, a heat utilizing means, a conduit extending from said heater to said means, and returning to said heater, and means to mechanically circulate liquid in said conduit toward said heater, said conduit having means to short circuit said liquid around said circulating means to avoid 75 passage of said liquid through said heater under predetermined conditions.

2. A heating apparatus for utilizing heat of a traveling body of viscous liquid comprising a heater, a heat utilizing means, a 80 conduit extending from said heater to said means and returning to said heater, a by-pass connected at its ends with the returning member of said main conduit, and a pump between the ends of said by-pass to 85 operate on liquid in said main conduit.

3. A heating apparatus for utilizing heat of a traveling body of viscous liquid comprising a heater, a heat utilizing means, a conduit extending from said heater to said 95 means and returning to said heater, a pump operating on the liquid in the return member of said conduit at a point adjacent said heater, and a by-pass connected with said conduit both at the suction and pressure 100 sides of said pump.

4. A heating apparatus for utilizing heat of a traveling body of viscous liquid comprising a heater, a heat utilizing means, a conduit extending from said heater to said 105 means and returning to said heater, a pump unit having a pump barrel constituting part of said conduit, a pipe extending at an angle from said conduit at one side of said pump, and a curved pipe communicating with said 110 pipe and with said conduit.

5. A heating apparatus utilizing heat of a traveling body of viscous liquid comprising a heater, a heat utilizing means, a conduit extending from said heater to said 115 means and returning to said heater, a pump unit having a pump barrel constituting part of said conduit, a pipe extending at an angle from said conduit at one side of said pump, and a pair of valved curved pipes communicating with said pipe and with said conduit.

6. A heating apparatus for utilizing heat of a traveling body of viscous liquid comprising a heater, a heat utilizing means, a conduit extending from said heater to said 125 means and returning to said heater, a pump unit having a pump barrel constituting part of said conduit, a pipe extending at an angle from said conduit at one side of said pump, and a curved pipe communicating with said 130

pipe and with said conduit, said curved pipe having a relief valve.

7. A heating apparatus for utilizing heat of a traveling body of viscous liquid comprising a heater, a heat utilizing means, a conduit extending from said heater to said means and returning to said heater, a pump connected with said return member of said conduit at a point adjacent said heater, an expansion pipe connected directly with the return member of said conduit at the suction side of said pump, and a relief valve having its casing communicating with the other member of said conduit between said heater and heat utilizing means.

8. A heating apparatus for utilizing heat of a traveling body of viscous liquid comprising a heater, a heat utilizing means, a conduit extending from said heater to said means and returning to said heater, a pump connected in the return member of said conduit at a point adjacent said heater, an expansion pipe connected with said return member of said conduit at the suction side of said pump, and a valve located in said return member of said conduit between said expansion pipe and said pump.

9. A heating apparatus for utilizing heat of a traveling body of viscous liquid comprising a heater, a heat utilizing means, a conduit extending from said heater to said means and returning to said heater, a pump connected in the return member of said conduit at a point adjacent said heater, an ex-

pansion pipe connected with said return member of said conduit at the suction side of the pump, a valve located in said return member of said conduit between said expansion pipe and said pump, and a liquid supply pipe communicating with said conduit at a point between said valve and said pump.

10. A heating apparatus for utilizing heat of a traveling body of viscous liquid comprising a heater, heat utilizing means, a conduit extending from said heater to said means and returning to said heater, a pump unit constituting a part of the return member of said conduit and having an upstanding pipe at the suction side of the pump connected with the conduit at the pressure side of said pump by a pair of curved pipes having valves, and a valve in said conduit between said curved pipes and said heater.

11. A heating apparatus for utilizing heat of a traveling body of viscous liquid comprising a heater, a heat utilizing means, a conduit extending from said heater to said means and returning to said heater, a pump connected in the return member of said conduit, means to supply additional liquid to said return member of said conduit at the suction side of the pump, and means whereby the liquid in said pump and a part of said additional supply may be returned from the pressure side of said pump to its suction side without entering said heater.

JOHN W. F. MACDONALD.
